UNITED STATES PATENT OFFICE.

WILLIAM A. SMITH, OF EASTON, PENNSYLVANIA, ASSIGNOR TO INGERSOLL-RAND COMPANY, OF JERSEY CITY, NEW JERSEY, A CORPORATION OF NEW JERSEY.

AUTOMATIC VALVE FOR INDEPENDENT-ROTATION DRILLS.

1,372,914.

Specification of Letters Patent. Patented Mar. 29, 1921.

Application filed May 11, 1918. Serial No. 233,978.

To all whom it may concern:

Be it known that I, WILLIAM A. SMITH, a citizen of the United States, residing at Easton, in the county of Northampton and State of Pennsylvania, have invented a certain new and useful Improvement in Automatic Valves for Independent-Rotation Drills, of which the following is a specification.

10 This invention relates to fluid operated percussive tools and in particular to a fluid operated percussive drill having a fluid operated motor for rotating the drill steel or bit.

15 The objects of the present invention are to provide a fluid operated tool of the above type with means to automatically control and regulate the amount of fluid supplied to the drill bit rotating motor which will permit a relatively small amount of fluid to pass from the main supply chest of the tool to the rotating motor when the drill is operating idly and will permit a greatly increased amount of fluid to pass to the 25 motor when the drill is operating under working conditions, and permit a proportionate amount of fluid to pass when the motor is operating under various conditions of load and speed. Furthermore, the means 30 employed serve to prevent a waste of fluid when the drill is operating idly as for instance when the drill is first started or while the drill is being advanced to the work or withdrawn therefrom, the means provided 35 for automatically controlling the supply of fluid to the rotating motor being independent of the means for supplying motive fluid to the percussive element.

With these and other objects in view the 40 present invention consists in the features of construction and operation set forth in the following specification and illustrated in the accompanying drawings forming a part hereof, in which:

45 Figure 1 shows a longitudinal view of a percussive tool containing the present invention;

Fig. 2, a sectional view of the controlling valve for the rotating motor.

50 Fig. 3, a longitudinal view of the forward portion of a percussive drill shown in section; and

Fig. 4, a sectional view taken on the line 4—4 of Fig. 3.

55 Referring more particularly to the draw-

ings, 1 refers to the cylinder of a percussive tool provided with the present invention. Within the cylinder 1 reciprocates the piston 2 which at the forward end of its stroke strikes the drill bit 3 retained in place within a chuck 4 in the forward end of the cylinder 1. A rotating motor 5 which comprises a pair of spur gears operates through gears 6 a gear 7 provided on the chuck 4 to rotate the chuck 4 simultaneously with the reciprocations of the piston 2.

Fluid for operating the piston and rotating motor is supplied from a suitable source (not shown) the conduit or passage for supplying the fluid to the rotating motor 5 being shown at 8. Within this conduit 8 is located the valve forming the subject matter of the present invention. This valve comprises a sleeve 9 secured transversely in the cylinder 1 by means of a threaded portion 10 and within the sleeve 9 is a hole 11 extending substantially throughout its length in which fits a valve 12. In the position of the valve as shown in Fig. 2 fluid passing through conduit 8 is allowed to leak past the outer head 13 of the valve 12 into a branch conduit 14 to the conduit 15 leading directly to the rotating motor 5. For this purpose the valve sleeve 9 is provided with slotted or cut out portions 16 to permit the fluid to pass through from the conduit 8 through the valve sleeve 9 and to the conduit 14. The slots or holes 16 cut into the sleeve 9 are so arranged that the valve in the position shown in the figures is not quite closed, at least a small quantity of fluid being permitted to pass through the sleeve 9 and past the valve 12 at all times, in order to insure that the pressure ahead of the motor will build up and be available to open the valve wider if the motor is stalled or retarded. The valve 12 is held in the position shown by means of a light spring 17 contained within the sleeve 9 and pressing against the outer head 13 of the valve 12. An additional inner valve head 18 is provided which balances the valve against endwise movement due to fluid pressure and for convenience the valve has short projections 19 at either end one of which serves to prevent the valve 12 from completely closing off the passage through the valve and the other serves to make the valve symmetrical and reversible.

The valve 12 when there is no pressure in

conduit 8 is held in partly closed position so that only a small amount of fluid may pass through the valve sleeve 9 and into conduit 15 to the motor 5. As soon as the drill steel 5 3 is forced against the rock and an increased amount of fluid is required to rotate the motor 5 the valve 12 moves to open the ports or slots 16 to allow a proportionately increased flow of fluid through conduit 15 to 10 rotate motor 5, which amount is dependent upon the pressure against the drill bit and the speed of rotation of the drill bit.

The branch conduit 14 is extended to intercept and join the lower end of the sleeve 9 and valve 12 so that the pressure on the farther side of the valve 12 from the fluid supply will be always acting on the end of the valve to press it upwardly and enlarge the opening through the valve 12 from conduit 8 to 15. The spring 17 is, however, just sufficiently strong to hold the valve 12 in the position shown when the pressure in the conduit 14 is very low and when pressure in conduit 14 increases above a given pressure 25 the fluid pressure acting against the piston head 18 or in other words the back pressure in conduit 15 unbalances the valve 12 and forces it to move upwardly and open more widely the passage from conduit 8 to 14.

30 In operation, when the drill is operating idly the motor 5 takes but very little fluid to operate it and after the motor comes up to its maximum speed the motor will operate on a pressure insufficient to open the valve; that is, the pressure within the conduit 14 will be insufficient to counteract the pressure of the spring 17. As soon, however, as resistance is encountered in rotating the drill bit 3, pressure increases in the conduits 14 35 and 15 and a back pressure is exerted against the valve dependent upon the speed of motor 5 and pressure on the drill bit 3 so that the pressure on the lower end of the inner head 18 is increased sufficiently to force the valve

to partially open and allow additional pressure to reach and operate the motor 5. When the resistance to the rotation of the drill bit 3 is withdrawn as when the drill is being removed from the hole the back pressure against the valve 12 within conduits 14 45 and 15 drops to a point sufficient to permit the spring 17 to expand and partially close the valve again so that the rotation is continued by a very small expenditure of fluid.

It is to be understood that the present 55 showing and description disclose only one specific embodiment of the present invention, and that other forms and modifications are included within the spirit and scope thereof, as expressed in the appended claim.

What I claim is:

In a fluid operated percussive tool the combination of a rotation motor, and a valve for automatically regulating the supply of motive fluid to the said motor, said valve comprising a valve chest having an inlet, and a supply passage leading to the motor, a sleeve in said chest having ports communicating with said inlet and supply passages, a spring pressed valve in said sleeve having 65 a stem and inner and outer heads, the outer head controlling the port in the sleeve leading to the motor, and the inner head closing said sleeve and having a projection adapted to bear on the valve chest and normally 70 maintain the valve open so as to permit a small quantity of fluid to flow past the outer head to the motor and keep the motor running under light load, and insure that the pressure ahead of the motor will build up 75 and be available to open the valve wider if the motor is stalled or retarded.

In testimony whereof, I have hereunto set my hand.

WILLIAM A. SMITH

Witness:

Wm. C. MORRIS.
